UNITED STATES PATENT OFFICE.

ARTHUR J. HOWARD, OF MALDEN, MASSACHUSETTS ASSIGNOR TO THE WIRE GRIP FASTENING COMPANY, OF CHICAGO, ILLINOIS.

DESIGN FOR A NAIL OR SLUG.

SPECIFICATION forming part of Design No. 24,764, dated October 15, 1895.

Application filed September 16, 1895. Serial No. 562,724. Term of patent 14 years.

To all whom it may concern:

Be it known that I, ARTHUR J. HOWARD, of Malden, in the county of Middlesex and State of Massachusetts, have invented and produced 5 a certain new and useful Design for a Nail or Slug, of which the following is a specification, reference being had to the accompanying drawings, forming a part thereof.

Figure 1 is an isometric view of a nail or 10 slug, showing my design; and Fig. 2 is an end view thereof.

The leading feature of my design, which relates to nails or slugs for ornamenting boot or shoe heels, consists in the longitudinal depressions having outwardly-flaring sides located in opposite sides of a nail or slug and 15 forming a thin narrow longitudinal fin between two larger cylindrical portions.

The body of the nail or slug has formed therein on opposite sides two longitudinal depressions f , their outwardly-flaring sides being formed by two larger cylindrical portions f' of the same diameter and symmetrically located, the inner portions of the depressions forming a thin narrow fin f^2 between the 25 larger cylindrical portions. 20

I claim—

The design for a nail or slug, substantially as set forth.

In testimony whereof I have signed my 30 name to this specification in the presence of two subscribing witnesses.

ARTHUR J. HOWARD.

Witnesses:

JOHN C. EDWARDS,
ALEX. C. PROUDFIT.
